AUTOMATIC GAS CUT-OFF

Howard H. Christensen, San Antonio, Tex.

Application June 24, 1933, Serial No. 677,403

6 Claims. (Cl. 137—153)

This invention relates to an improved gas cut-off for gas burning appliances.

The primary object of my invention is to provide a simple and effective gas cut-off that will positively cut the gas off to any gas burning appliance or appliances when the pressure of the gas in the main gas line decreases to such an extent that the flame in the gas burning appliance is extinguished.

10 Another object of my invention is in the construction whereby the flow of gas to the gas burning appliance is cut off indefinitely and must be reopened manually after same has automatically cut off.

15 Still another object is in its construction whereby the device is fool-proof and tamper-proof as well as being fully protected from weather conditions. In the event anyone should turn the mechanism on the gas cut-off accidentally while the gas burning appliances are burning it will not effect the cut-off and will not cut the gas off to said appliances, thereby avoiding and eliminating the hazard of explosions and fires.

20 Another feature of the invention is the fact that the device has only one moving part on its exterior, said part capable of revolving in either direction for the purpose of reopening the flow of gas to the gas burning appliances, after having been automatically cut off due to a decided decrease in the pressure of the gas in the main gas line or its failure to flow.

25 With these chief objects in view, the invention has particular reference to its salient features of construction and arrangement of parts by which the said objects are obtained and which will be enumerated in the course of the following description of detail and illustration.

30 In the accompanying drawings like characters or references indicate like parts in the several views, and:

Figure 1 is a vertical cross-sectional view of the invention, showing the device in a locked position.

Figure 2 is a plan view of the revolving cap latch releasing member.

Figure 3 is an elevational view of the collar male engaging member.

Figure 4 is an elevational view of the tubular member forming a receptacle at its lower end and provided with an eccentric ear extending therefrom.

Figure 5 is a fragmentary vertical sectional view through the casing; showing the parts therein in elevation and disclosing the position of the same unlocked.

Figure 6 is a modification of the inverted cup float partly in elevation and partly in section.

Proceeding now more in detail with the drawings, attention is directed to Figure 1, in which, is illustrated the invention in a locked position with the gas cut off. The gas cut-off is provided with a casing 1 and a threaded cover 2. The cover 2 is provided with a tubular member 3 extending downward into an annular receptacle 4. The receptacle 4 is filled with mercury 5 thereby preventing any escape of gas therethrough. An eccentric cam ear 6 extends from the outer periphery of the receptacle 4. The receptacle 4 has an elongated tubular member 7 extending upward through the cover 2 and is threaded at its upper portion. A collar 8 is screwed on the tubular member 7, and is held in a fixed position on the member 7 by means of set screw 9. The collar 8 is provided with openings 10 in its lower end, and has a male engaging head 11. The male engaging head 11 engages the revolving cap member 12. This cap 12 is counter-sunk in its center to permit a pentagon shaped lock nut 13 to be screwed onto tubular member 7. A threaded plug 14 is screwed into the upper end of the tubular member 7. The revolving cap 12 forms a housing for the cover 2 and the parts extending therethrough. The cover 2 has a conical recess 15 in its upper portion. Two or more fingers 16 of irregular lengths are pivotally mounted on the tubular member 3, said fingers 16 extending downward and inward. The fingers 16 are capable of holding and latching an inverted cup 17 in a downward locked position by means of an elongated guide stem 18 which extends upward into the tubular member 7, this stem 18 is provided with a shoulder 19 and is inwardly tapered on its top portion 20 which acts as the latching means. The inverted cup 17 is attached to the stem 18. The shoulder 19 is provided with ports 21. A series of openings 22 are provided in the lower end of the inverted cup 17. An auxiliary buoyant member 23 is situated on the extreme lower end of the cup 17. The casing 1 has a quantity of mercury 24 inside its lower portion. A mercury drain plug 25 is screwed into the casing 1. The casing 1 is provided with a gas inlet 26 and outlet 27. A tubular stem 28 extends upward within the casing 1 at its gas inlet 26. When the gas cut-off has been installed, the cap 12 is removed by removing pentagon lock nut 13, then a predetermined amount of mercury is poured into the conical recess 15 whereby the mercury will flow through ports 10 in the collar 9 down through the tubular member 3 into the receptacle 4. By continuing to pour the mercury 55

into the receptacle 4 it will overflow allowing the mercury to run into the trap at the lower end of the casing 1. In the event any mercury falls into the tapered recess 29 of the shoulder 19, it will 5 pass out through ports 21. The cap 12 and locknut 13 is then replaced.

The gas cut-off is now ready for operation, and attention is directed to Figure 5 wherein the device is in an unlocked position and shows the inverted cup 17 in a raised position due to its buoyancy and the pressure of gas passing within and through the cup 17. In this view is also shown the fingers 16 disengaged. It is apparent when the pressure decreases to any predetermined degree or the gas entirely ceases to flow from any cause, the cup 17 will settle downward into the mercury allowing the fingers 16 to fall into the recess 20 of the shoulder 19, thereby locking the inverted cup 17 in a submerged position which 20 prevents the gas from flowing through the ports 22, in the event the gas starts flowing again.

At this point the gas cut-off is now in a locked and cut off position as illustrated in Figure 1. To reopen and unlock the cut-off and to permit 25 the gas to flow again the cap 12 is revolved in either direction one complete revolution, whereby the eccentric cam ear 6 is revolved due to the fact that it is attached to receptacle 4 which has an elongated tubular member 7 extending upward 30 and is provided with a threaded collar 8 and held in a fixed position on the tubular member 7 by means of set screw 9. The collar 9 engages the cap 12 by means of male and female joint 11. It will readily be seen that when the eccentric ear 6 35 is revolved one complete revolution the ear 6 will disengage and unlock the longest of the fingers 16 one at a time until all the fingers 16 are disengaged and unlocked as shown in Figure 5. The purpose of having the fingers 16 of irregular 40 lengths is to cause the unlocking and disengagement of the fingers 16 more positive.

Figure 6 is a modification of the inverted cup 17 which is provided with an auxiliary inverted cup 29 and buoyant member 30.

45 The gas cut-off is adapted to be positioned either before or between the conventional gas meter and the gas pipe leading to the various gas burning appliances. In either event the flow of gas will pass into the gas cut-off through the inlet 26 and tubular member 28 and through the 50 port holes 22 in the inverted cup 17 and will then egress through the outlet 27.

While only one form of each element in the 55 invention has been described herein it should be understood that the invention is capable of considerable variation, and such variation as is within the scope of the annexed claims is considered within the spirit of the invention.

I claim:

60 1. In a gas cut-off of the character described comprising a housing, a gas inlet and a gas outlet, a liquid reservoir in the bottom portion of said housing, a buoyant gas receiving member capable of floating on said fluid having gas port 65 holes near the bottom thereof, said gas receiving buoyant member capable of submerging its bottom portion into said liquid and stopping the flow of gas therethrough when the gas pressure decreases to a predetermined degree, a guide stem 70 member extending upwardly from said buoyant member and having an annular shoulder thereon, a plurality of pivotally suspended fingers of irregular lengths extending downward within said housing adapted to engage the shoulder and lock 75 the buoyant member in a closed position until

manually unlocked, and rotatable exterior means for disengaging and unlocking said fingers and said buoyant member allowing gas to flow through the device.

2. In a gas cut-off comprising a housing and 5 a gas tight cover, a gas inlet and a gas outlet, a liquid reservoir in the bottom portion of the housing, an inverted buoyant cup member disposed in said liquid reservoir, gas port holes within the lower portion of the inverted cup member, said cup member adapted to cut off and reopen the flow of gas through the device by actuating in the liquid reservoir, an elongated guide stem connected to the top of the inverted cup member, said guide stem being provided with 10 a locking shoulder, pivotally mounted locking fingers extending downwardly within the housing adapted to engage the shoulder and automatically locking the inverted cup member in a submerged position in the liquid reservoir and preventing the 15 flow of gas therethrough when the gas pressure decreases decidedly, said locking fingers being of irregular lengths, and capable of disengagement with the shoulder one at a time, a rotatable cap 20 exteriorly positioned on top of the said cover having a tubular member connected and extending downward through the cover and into the housing, said tubular member forming a cup at its lower end, a quantity of fluid in said cup, a tubular stem extending downward from said cover into said liquid in the cup preventing the 25 escapement of gas therethrough, a laterally extending ear on said cup member, said exterior cap, connected tubular member, cup member and eccentric ear being all capable of rotation in 30 either direction and simultaneously manually operated to move the ear into successive engagement with the finger to unlock and disengage said fingers, said cover having a conical recess 35 for filling said fluid cup with liquid and permitting the liquid to overflow in said cup allowing the fluid to fall into the fluid reservoir in the bottom of the housing, as herein described.

3. In a gas cut-off comprising a housing, a 45 cover closing said housing gas-tight, a gas inlet, and a gas outlet, a tubular stem extending upward from said inlet within the housing forming a fluid reservoir therein, a buoyant member for closing and opening said inlet, means operatively connected within said housing to automatically lock said buoyant member in a 50 submerged cut off position, an exterior manually operated member having means extending into said housing to unlock and allow gas to flow 55 through the device, a fluid sealing means to prevent the escapement of gas through the upper portion of the device, means for filling said fluid sealing means, the fluid reservoir being supplied with fluid, that overflows from the fluid sealing 60 means.

4. In an automatic gas cut-off, a casing, a gas inlet in the bottom thereof, a gas outlet, the lower portion of the casing constituting a liquid reservoir, a buoyant cup member movable over the 65 gas inlet and having a series of ports in the lower portion thereof through which the gas flows when the cup member is in its raised position and the ports are positioned above the liquid in said reservoir, the cup member being lowered to sub- 70 merge the ports in the liquid when the gas pressure decreases below a predetermined degree to cut off the flow of the gas to the outlet, a latch pivotally suspended within the upper part of the casing, means carried by the cup member en- 75

gaged by the latch to lock the cup in its lowered position, a manually rotatable member arranged in the top of the casing, and a trip element carried by the rotatable member for releasing the latch to permit the return of the cup member to its normally raised position when the gas pressure reaches a predetermined pressure.

5. In an automatic gas cut-off, a casing, a gas inlet in the bottom thereof, a gas outlet, the lower portion of the casing constituting a liquid reservoir, a buoyant cup member movable over the gas inlet and having a series of ports in the lower portion thereof through which the gas flows when the cup member is in its raised position and the 10 ports are positioned above the liquid in said reservoir, the cup member being lowered to submerge the ports in the liquid when the gas pressure decreases below a predetermined degree to cut off the flow of the gas to the outlet, a stem 15 extending upwardly from the top of the cup member, a shoulder formed on said stem, a plurality of fingers pivotally suspended at their upper ends in the upper portion of the casing, the lower free ends of the finger being adapted to engage the shoulder to lock the cup in its lowered position, a manually rotatable member arranged in the top of the casing, and a laterally extending trip element carried by the rotatable member 20 and adapted to successively engage the pivoted fingers to release the same from engagement with said shoulder, whereby to permit the return of the cup member to its normally raised position when the gas pressure reaches a predetermined degree.

25

position when the gas pressure again reaches a predetermined degree.

6. In an automatic gas cut-off, a casing, a gas inlet in the bottom thereof, a gas outlet, the lower portion of the casing constituting a liquid reservoir, a buoyant cup member movable over the gas inlet and having a series of ports in the lower portion thereof through which the gas flows when the cup member is in its raised position and the ports are positioned above the liquid in said reservoir, the cup member being lowered to submerge the ports in the liquid when the gas pressure decreases below a predetermined degree to cut off the flow of the gas to the outlet, a manually rotatable cap in the top of the 15 casing, a fluid receiving receptacle depending from the cap, the liquid in the reservoir being supplied thereto by the overflow from said receptacle, a plurality of various length fingers pivotally suspended at their upper ends within 20 the upper portion of the casing, a shoulder element carried by said cup and with which the free ends of the fingers engage to lock the cup in its lowered position, and a trip forming ear extending laterally from the receptacle and 25 adapted to successively engage the pivoted fingers to release the same from engagement with the shoulder when the cap is rotated, whereby to permit the return of the cup member to its normally raised position when the gas pressure reaches a predetermined degree.

30

HOWARD H. CHRISTENSEN.
